UNITED STATES PATENT OFFICE.

JAMES G. ROSS, OF SEATTLE, WASHINGTON, ASSIGNOR OF FORTY PER CENT TO ELSIE GUYER, OF SEATTLE, WASHINGTON.

STREET SIGN.

Application filed July 27, 1927. Serial No. 208,839.

This invention relates to signs and more particularly to a sign adapted to be suspended from an overhead support at a street intersection to indicate the names of the intersecting streets.

One object of the invention is to so construct the sign that it may be firmly engaged with its overhead support and prevented from becoming detached from the support or having movement which would prevent it from being easily read.

Another object of the invention is to form the sign of strong sheet metal and to so mark its faces that it may not only indicate the names of the intersecting streets but also indicate the street numbers of the blocks adjoining the intersection.

The invention is illustrated in the accompanying drawing, wherein

20 Figure 1 is a side elevation showing the improved sign suspended from an arm carried by a light post;

Fig. 2 is an enlarged view of the sign;

25 Fig. 3 is a vertical sectional view through the sign, and

Fig. 4 is fragmentary sectional view showing a modified means for connecting the sign with its supporting arm.

The sign, which is indicated in general by 30 the numeral 1, has been shown suspended from a depending end portion 2 of an arm 3 secured to a lamp post 4 in any desired manner and projecting transversely therefrom. This arm 3 may be disposed at any height de-

35 sired upon the lamp post 4 so that the sign may be easily read by persons approaching a street intersection upon a sidewalk or in the street. The sign is formed of strong sheet metal and is preferably substantially rectangular in shape and disposed to provide side

40 corners and upper and lower corners. A neck 5 projects from the upper corner of the sign and intermediate its length is bent to provide an offset upper portion 6 having a

45 shoulder 7 at its lower end. By referring to Fig. 2, it will be seen that the lower end of the depending portion 2 of the suspending arm 3 tapers to a point and, therefore, when forming the offset upper portion 6, the neck is so

50 bent that the shoulder 7 will conform to the taper of the lower end of the suspending arm. It will be understood, however, that, if desired, the depending end of the suspending arm may have its lower end cut straight

55 across in which case the neck would be simi-

larly bent in order to have flat contact engagement with the lower end of the suspending arm. In order to securely but releasably retain the sign in engagement with the depending end portion of the suspending arm, I 60 may employ bolts 8 which are passed through aligned openings 9 and 10 in the arm and neck and carries a securing nut 11 or a tongue 12 may be cut from the depending arm, as shown in Fig. 4, and after being passed through an 65 opening in the neck bent into engagement with the outer face of the offset upper end portion of the neck. In either case the sign will be securely but releasably held in engagement with the depending free end portion of its suspending arm. It should be further noted that since the lower end of the depending suspending arm has flat contacting engagement with the shoulder 7 movement of the sign transversely of the suspending arm 70 will be prevented and, therefore, the sign will be retained in the vertical position shown in Figs. 1 and 2. In the preferred form, each face of the sign is bent to define a vertically extending arrow 13 having a head 14 at its 75 lower end and a horizontally extending arrow 15 having heads 16 at its ends. The name of one street is marked upon the arrow or strip 13, as shown in Fig. 2, and the numeral designating the major numeral of the 80 street addresses of houses in the next block. The cross strip or arrow 15 also bears the name of the intersecting street, compass points, and the numerals constituting the major numerals of houses in the adjoining 85 blocks. Therefore, a person walking along a street which may be 8th Avenue, as shown in Fig. 2, may know that he is at the intersection of 8th Avenue and Market Street and by reading the sign will know that upon crossing 90 Market Street he will be in the 200 block of 8th Avenue. If he desires to turn into Market Street, he will know that the adjoining block to the east of 8th Avenue is the 100 block of Market Street, whereas the adjoining 95 block of Market Street to the west side of 8th Avenue is the 500 block. It is preferred to color the strips 13 and 15 of the sign white and the remainder of the sign and street names black so that the sign may be very 105 easily read but other color schemes may be substituted if so desired.

Having thus described the invention, I claim:

1. In a device of the character described, a 110

support including a depending arm, a sign plate having a neck bent intermediate its length to provide an offset upper portion having a shoulder at its lower end, and a tongue 5 struck from said arm and passed through an opening in the offset upper portion of said neck to releasably retain the neck and arm in overlapped relation to each other with the lower end of the arm bearing against said shoulder.

2. A street intersection sign comprising a flat body having pointed side and lower corners, and an attaching neck extending from the upper end of said body and having an offset upper portion adapted to be secured to a support, and formed with a V-shaped shoul-

der to bear against the lower end of the support, said body having a face marked to define a vertically extending strip and a cross strip, intersecting the vertical strip, the vertical strip terminating in an arrow head at 20 the lower corner portion of the body and having its upper end portion extending along said neck and shaped to define a feathered end for the arrow by the V-shaped shoulder, the cross strip terminating in arrow heads at the side 25 corners of the body, said strips having the names of intersecting streets provided thereon.

In testimony whereof I affix my signature.

JAMES G. ROSS. [L.S.]
